RELEASABLE WELL PACKER

Reuben C. Baker, Coalinga, Calif., assignor to
 Baker Oil Tools, Inc., Vernon, Calif., a corpora-
 tion of California

Application November 14, 1941, Serial No. 419,061

8 Claims. (Cl. 166—12)

The present invention relates to well packers, and more particularly to packers of the releasable type capable of employment in the performance of many operations in a well bore, including the cementing, acidizing or repressuring of oil wells, testing casing for holes, and testing formations for fluid permeability, break down pressures, or productivity.

An object of the present invention is to provide an improved well packer capable of being set, released and reset mechanically in a casing without the necessity for withdrawing it to the surface of the well bore.

Still another object of the invention is to provide an improved well packer adapted to have its packing and anchoring members mechanically set against the wall of a casing, and in which such packing and anchoring members are also mechanically releasable from such engagement.

A further object of the invention is to provide an improved well packer having packing and anchoring members adapted for engagement with the well casing, in which these members are all releasable positively from the surface of the well bore through rotation of a tubular string attached to the well packer.

Another object of the invention is to maintain the packing and anchoring members of a well packer locked in retracted position while the packer is being lowered or elevated in a well bore, and to preclude unlocking thereof upon inadvertent turning of the tubular string to which the well packer is attached.

The invention has other objects that will become apparent from a consideration of the embodiment shown in the drawings accompanying and forming part of the present specification. This form will now be described in detail, but it is to be understood that such detailed description is not to be taken in a limited sense, since the scope of the invention is best defined by the claims appended hereto.

Referring to the drawings:

Figure 1 is a longitudinal view, partly in section and partly in elevation, of a well packer with its parts in retracted position for movement through a well bore or casing;

Figure 2 is a view similar to Figure 1 with the packer disclosed as anchored in packed off condition within a well casing;

Figure 3 is a view similar to Figure 1, with certain of the packer parts disclosed in still another relative position;

Figure 4 is a fragmentary longitudinal section 55

on an enlarged scale of part of the device disclosed in Figure 3;

Figure 5 is a side elevation as seen from the right of Figure 4;

Figure 6 is a section taken along the line 6—6 in Figure 4;

Figure 7 is a cross-section taken along the line 7—7 in Figure 3; and

Figure 8 is a cross-section taken along the line 8—8 in Figure 3.

The well packer A is adapted to be run in a well bore or casing B on the end of a tubular running-in string C threaded or otherwise attached to the upper end of the tubular mandrel 10 of the packer. For convenience of manufacture, this mandrel is made in two parts, with its lower section 11 welded or otherwise suitably attached to the upper section 12. The lower section 11 is provided with external left hand threads 13 engaging companion threads at the enlarged upper end 14 of the tubular body 15 of the packer.

The lower section 16 of this body is reduced in diameter to provide an abutment 17 adapted to cooperate with an inturned flange 18 formed on the lower end of a tapered expander 19 mounted on the body 15. A key 20 is secured to the exterior of the enlarged body portion 14 for reception within a keyway 21 in the expander so as to permit relative longitudinal movement between the body 15 and expander 19 while preventing rotation therebetween. Any foreign matter which might enter the keyway 21 or the annular space between the abutment 17 and flange 18 when they are separated may pass therefrom through bleeder holes 22 extending through the expander between its internal and external surfaces.

A packing actuator in the form of a guide member 23 is threaded on the lower end of the body. This packing actuator is movable toward the expander 19 for the purpose of engaging the lower end of the packing sleeve 24 surrounding the body and forcing it against the underside of the expander 19 and outwardly against the casing B, to effect an annular seal between it and the body 15.

A plurality of slips 25 is disposed around the mandrel 10 for cooperation with the tapered expander 19 in moving to and from anchoring engagement with the wall of the casing. Each of these slips has wickers 26 on its exterior surface adapted to grip the casing, and an interior tapered surface 27 cooperable with a companion tapered surface 28 comprising the bottom of a

channel 29 formed in the expander, so that relative longitudinal movement between the expander 19 and slips 25 moves the latter radially to and from the casing. For the purpose of holding the slips properly assembled on the expander 19 and within the channels 29, they are formed with outwardly and oppositely directed tongues 38 fitting within grooves 31 formed in the sides of the channels. Because of this construction, the slips 25 are keyed to the expander to permit relative sliding movement therebetween in positively shifting the slips both toward and away from the casing. The extent of outward movement of each slip 25 upon moving downwardly on the expander 19 is limited by a stop screw 32 on the latter member movable within a longitudinal groove 33 in the underside of the slip and engageable with the end 34 of this groove.

The slips 25 are held together for joint movement along the tapered expander 19 to and from engagement with the casing by providing recesses 35 in their side faces which receive outwardly extending fingers 36 for guiding the slips radially to and from the casing, and for preventing their longitudinal movement except in unison by engaging the ends of the recesses 35. These fingers 36 are integral with a sleeve 37 slidable on the mandrel 10, which has an upper set of outwardly extending fingers 38 for receiving heads 39 provided on the upper ends of the slips engageable with a stop ring 40 secured around the upper fingers 38 by screws 41 or the like, for the purpose of limiting the extent of outward movement of the slips 25 and to hold them in assembled position.

This sleeve 37, and the slips 25 assembled thereon, are coupled to a drag and lock device. This device consists of a lock collar 42 slidable on the mandrel 10 and having a J or other suitably shaped slot 43 formed therein for the purpose of receiving a lock pin 44 fastened to the mandrel. A plurality of circumferentially spaced outwardly bowed springs 45 are disposed around the mandrel with their lower ends resting on the lower portion of the locking collar and held thereagainst in assembled position by a ring 46 fastened to this portion of the collar by a plurality of screws 47. The upper ends of the springs are secured to a slidable upper drag collar 48 by an upper ring 49 suitably fastened to the collar, as by the screws 50.

The drag and locking device is coupled to the slip assembly by means of a sectional tie or coupling ring 51 secured to the locking collar 42 by the screws 52, and having a lower inturned flange 53 receiving and fitting under an external flange 54 at the upper end of the slip sleeve 37. Rotation of the tubular string C, mandrel 10 and drag device is permitted without corresponding rotation of the slip assembly sleeve 37 and slips 25, due to the swivel type of connection provided by the lower end 53 of the coupling ring 51 and sleeve flange 54.

The well packer is run in the well casing on the end of the tubular string C, with the locking pin 44 positioned in the locking foot portion 55 of the J-slot 43, so as to hold the slips 25 in an upward retracted position on the tapered expander 19, and the packing sleeve 24 in retracted position free from engagement with the casing (as in Figure 1). Upon reaching the desired setting point in the casing, the tubular string C is turned a partial revolution in a counter-clockwise direction (as seen from the surface of the well bore) so as to position the pin 44 at the

lower end of the longitudinal leg portion 56 of the J-slot at its point of juncture with the foot portion 55, which will then allow the mandrel 10 to be shifted upwardly within the locking collar 42. Such upward movement of the mandrel 10 and its connected body 15 is obtained by elevating the tubular string C, which movement is transmitted through the packing sleeve 24 to elevate the tapered expander 19 within the slips 25. Since these slips are held stationary by the friction action of the drag springs 45 against the casing, upward movement of the expander 19 within the slips forces the latter outwardly into engagement with the casing. After the slips have engaged the casing, the expander can no longer move upwardly, but the mandrel 10 and body 15 can still be elevated due to the slidable key connection 26, 28 between the body and expander. A continuation of the upward movement of the mandrel and body can then compress the packing sleeve 24 between the expander 19 and guide 23, forcing it into sealing engagement with the casing B (see Figure 2).

The tool is now anchored in packed off condition within the well casing, preventing fluid pumped down through the tubular string to a point below the packer from passing around it or forcing the packer up the casing. Pressure exerted from below on the well packer forces the guide 23 more firmly against the packing 24 and causes it to seal off to a greater extent against the casing B and body 15, and also acts through the packing to wedge the expander 19 more firmly into the slips 25 and attach them more securely to the casing.

If it is thereafter desired to release the well packer from the casing, the tubular string C is merely lowered to correspondingly lower the mandrel 10 and body 15 with respect to the slips 25 and expander 19. As the guide 23 is lowered away from the packing 24 the latter is permitted to elongate once again and move back to its retracted position free from contact with the casing. Upon lowering of the body sufficiently, its abutment 17 engages the inturned flange 18 at the lower end of the expander, forcing it downwardly out of wedging relation within the slips 25. Upon release of this wedged expander, the slips disengage from the casing. Lowering of the body and expander sufficiently moves the slips inwardly to their fully retracted position, due to the coaction of the sides of the grooves 31 in the expander with the tongues 38 on the sides of the slips. It is again pointed out that the drag device tends to resist longitudinal movement of the slips, so that the lowering of the expander is accompanied by forcible retraction of the slips away from the casing back to the approximate retracted position disclosed in Figure 1.

The lowering of the mandrel 10 for the purpose of retracting the slips and packing positions the locking pin 44 at the lower end of the longitudinal leg portion 56 of the J-slot once again, allowing the turning of the tubular string C in a clockwise direction (as seen from the surface of the well bore) to again position the lock pin 44 at the end of the locking foot portion 54 of the slot, preventing material longitudinal movement between the packer parts to occur. With the parts in this position, it is apparent that the drag device 45, 48, 42 is forced to move with the mandrel 10 longitudinally through the casing. The friction springs 45 have sufficient tension to resist movement of the slips 25 when it is desired to set or release them, but this friction is of insuf-

ficient magnitude to prevent lowering or elevation of the well packer as a unit through the well casing.

Should release of the packer from its set position by lowering the tubular string C, mandrel 10 and body 15 be unobtainable, due to some condition in the well bore, a greater force can be exerted to force the parts to retracted position. The threaded connection 13 between the lower mandrel section 11 and the upper portion 14 of the body 15 forms a jack screw which can forcibly move the slips 25 and expander 19 relatively in longitudinal directions away from each other upon rotation of the tubular string in the proper direction. Since the threaded connection between the lower mandrel part 11 and body 14 is preferably a left hand one, such forcible longitudinal movement is induced through turning of the tubular string in a clockwise direction.

If the well packer A cannot be released upon imposing a downwardly directed force on it through lowering of the tubular string, the casing engaging packer parts 24, 25 are held with sufficient force as to prevent their rotation. Thus, the slips 25 cannot rotate in the casing, and due to their manner of assembly on the expander 19, they correspondingly prevent this member from rotating. Similarly, the key connection 20, 21 between the expander and body 15 prevents the latter from turning, although it will permit relative longitudinal movement between the two members to occur. Rotation of the tubular string and mandrel threads the lower mandrel section 11 from the body 15 to effect this relative longitudinal movement. As these members move in relatively opposite directions due to the rotation of the mandrel, an outwardly directed flange or abutment 57 at the upper end of the lower mandrel section 11 engages the underside of the slip sleeve 31, and through the fingers 36 exerts a force on the slips 25. Such longitudinal movement also engages the body abutment 17 with the expander flange 18, causing further rotation of the tubular string and mandrel to forcibly move the expander and slips relatively in directions away from each other, and move the slips forcibly inwardly along the tapered surface 28 of the expander to their retracted position. The well packer is now free from the casing and may be removed to the surface of the well bore (see Figure 3).

It is to be noted that the lock pin 44 is in the longitudinal J-slot portion 56 while the tubular string C is being rotated, effectively coupling the mandrel 10 and drag device 45, 42 for rotation together. Although the springs 45 resist movement of the drag collars 48, 42 and slips 25, they do not exert sufficient frictional force to prevent rotation of the entire drag assembly with the tubular string. However, such rotation is not accompanied by rotation of the slips 25 and tapered expander 19, because of the swivel connection 53, 54 provided between the drag assembly and the slip ring 51.

It is therefore apparent that a releasable well packer has been provided capable of being set mechanically in packed off condition within a well casing, and normally released from such set position by merely lowering the tubular string to which the packer is attached. In the event that insufficient force can be exerted to effect release through a mere straight lowering of the tubular string, the force available at the surface of the well bore can be greatly multiplied by turning the tubular string, through use of the jack

screw connection 13 between the mandrel 10 and packer body 15.

It may sometimes occur that the lower portion of the tool is entirely cemented in or frozen to the casing, precluding release of the entire tool even upon employing the jack screw feature. Should this situation arise, rotation of the tubular string would be continued until the lower mandrel 11 was entirely unscrewed from the packer body 15, whereupon all of the tool parts with the exception of the body 15, expander 19, packing sleeve 24, and guide 23 can be removed from the well casing. The elements specifically listed are made of drillable materials and are removable from the well casing, if necessary, by a suitable drilling operation, in a well known manner. Since the expander 19 is made of readily drillable material, complete unscrewing of the mandrel will elevate the slips 25 and cause their tongues 30 to break off the outer side of the grooves 31 from the remainder of the expander, thereby freeing the slips from the expander. If desired, however, the parts can be so arranged and proportioned as to allow the slips 25 to be removed completely from the expander 19 and its grooves upon complete unthreading of the mandrel 12 from the body 16.

The tool may also incorporate a device for preventing its unlocking until desired. To achieve this purpose, a coil actuating spring 60 surrounds the mandrel 10 with its lower end attached to the upper drag collar 48 by the screw 61 and its upper end attached by a screw 62 to a ring 63 suitably fastened to the mandrel 10 by another screw 64. The coil spring 60 is so wound as to exert a turning force on the drag device tending to move it to the right or counter-clockwise (as seen from the surface of the well bore) so as to hold the end of the locking slot portion 55 against the lock pin 44, and yieldably prevent inadvertent rotational movement between this pin 44 and locking collar 42, which might position the pin in the longitudinal or unlocking portion 56 of the J-slot; a relationship essential to setting of the tool.

I claim:

1. A well device, which includes a tubular body, an expander slidably mounted on said body, means cooperable with said expander for anchoring said device in a well casing, a rotatable tubular mandrel, means connecting said mandrel to said body whereby rotation of said mandrel with respect to said body is adapted to effect relative longitudinal movement between said body and mandrel, and means on said rotatable mandrel and body for transmitting such longitudinal movement to both said anchoring means and expander to forcibly move them relatively to each other in longitudinal directions away from each other to retract said anchoring means from anchoring engagement with the well casing.

2. A well device, which includes a tubular body, expander means slidably keyed on said body, means cooperable with said expander means for anchoring said device in a well casing, a tubular mandrel threaded attached to said body, an abutment on said body adapted to engage one of said means, an abutment on said mandrel adapted to engage the other of said means, said threaded attachment being such as to effect relative longitudinal movement between said mandrel and body upon relative rotation between said mandrel and body to cause said abutments to engage said expander means and anchoring means and forcibly move them relatively to each other in longitudinal

directions away from each other to retract said anchoring means from anchoring engagement with the well casing.

3. A well device, which includes a tubular body, a tapered expander slidably keyed on said body, slips cooperable with said expander for anchoring said device in a well casing, means coupling said slips for movement in unison, a tubular mandrel threadedly attached to said body, an abutment on said body for engagement with said expander, an abutment on said mandrel for engagement with said coupling means, said abutments engaging said expander and coupling means upon relative rotation between said mandrel and body to forcibly move said expander and slips relatively to each other in longitudinal directions away from each other to retract said slips from anchoring engagement with the well casing.

4. A well device, which includes a tubular body, a tapered expander slidably keyed on said body, slips cooperable with said expander for anchoring said device in a well casing, a tubular mandrel threadedly attached to said body, means slidable on said mandrel and coupling said slips for movement in unison, an abutment on said body for engagement with said expander, an abutment on said mandrel for engagement with said coupling means, said abutments engaging said expander and coupling means upon relative rotation between said mandrel and body to forcibly move said expander and slips relatively to each other in longitudinal directions away from each other to retract said slips from anchoring engagement with the well casing, and means engageable with said casing for resisting longitudinal movement of said slips therewithin.

5. A well device, which includes a tubular body, an expander slidably keyed on said body and provided with portions inclined upwardly and inwardly, slips engaging and movable along said inclined expander portions for anchoring said device in a well casing, means above said expander coupling said slips for movement in unison, a tubular mandrel threadedly attached to said body and extending upwardly therefrom, an abutment on said body for engagement with said expander, an abutment on said mandrel for engagement with said coupling means, said abutments engaging said expander and coupling means upon relative rotation between said mandrel and body to forcibly move said expander and slips relatively to each other in longitudinal directions away from each other to retract said slips from anchoring engagement with the well casing.

6. A well packer, which includes a tubular body, a tubular mandrel threaded within said body and extending upwardly therefrom, a packing sleeve on said body, a tapered expander slidably keyed on said body above said packing sleeve, slips cooperable with said expander for anchoring said packer in a well casing, a sleeve slidably mount-

ed on said mandrel supporting said slips with respect to said expander, friction means adapted to frictionally engage said well casing slidably on said mandrel and rotatively coupled to said sleeve to permit said friction means to rotate without corresponding rotation of said slips, said friction means resisting longitudinal movement of said slips in said casing, whereby upward longitudinal movement of said mandrel and body compresses said packing sleeve between said body and casing and moves said expander within said slips to shift them into anchoring engagement with said casing, an abutment on said mandrel engageable with said slip sleeve, an abutment on said body engageable with said expander, said abutments engaging said expander and slip sleeve to forcibly move said expander and slips relatively to each other in longitudinal directions away from each other upon unscrewing movement of said mandrel relative to said body, and selectively positionable locking instrumentalities on said mandrel and friction means for preventing relative longitudinal movement between said slips and expander or to permit such movement.

7. A well device, which includes a tubular body, expander means slidable on said body, means cooperable with said expander means for anchoring said device in a well casing, a tubular mandrel, an attachment securing said mandrel to said body, an abutment on said body adapted to engage one of said means, an abutment on said mandrel adapted to engage the other of said means, said attachment being such as to effect relative longitudinal movement between said mandrel and body upon relative rotation between said mandrel and body to cause said abutments to engage said expander means and anchoring means and forcibly move them relatively to each other in longitudinal directions away from each other to retract said anchoring means from anchoring engagement with the well casing.

8. A well device, which includes a tubular body, an expander slidable on said body, slips cooperable with said expander for anchoring said device in a well casing, means coupling said slips for movement in unison, a tubular mandrel, an attachment securing said mandrel to said body, an abutment on said body for engagement with said expander, an abutment on said mandrel for engagement with said coupling means, said attachment between said mandrel and body being such as to effect relative longitudinal movement between said mandrel and body upon relative rotation between said mandrel and body to cause said abutments to engage said expander and coupling means and forcibly move said expander and slips relatively to each other in longitudinal directions away from each other to retract said slips from anchoring engagement with the well casing.

REUBEN C. BAKER.
